UNITED STATES PATENT OFFICE.

THOMAS HANSON, OF NEW YORK, N. Y.

FAUCET AND WASTE-VALVE.

SPECIFICATION forming part of Letters Patent No. 235,429, dated December 14, 1880.

Application filed March 13, 1880. (No model.)

To all whom it may concern:

Be it known that I, THOMAS HANSON, of the city of New York, in the county and State of New York, have invented certain new and useful Improvements in Faucets and Waste-Valves, of which the following is a specification.

My invention consists in the combination of a shell or chamber, a shaft or spindle arranged longitudinally therein and adapted to be turned or oscillated, two water-inlets extending transversely to said shell or chamber and each provided with an outwardly-opening valve, a delivery-outlet, and two cams upon said shaft or spindle, for opening said valves, so arranged that the said valves may be opened simultaneously or separately to permit either hot and cold water to be drawn separately or together.

It also consists in the combination, with the above, of a waste-valve, which may be operated by lifting the shaft or spindle, to allow the water to run from a basin or other article with which the faucet is used.

In the accompanying drawings, Figure 1 represents a central vertical section through a device embodying my invention, and Fig. 2 represents a horizontal section thereof upon the dotted line *x x*, Fig. 1.

Similar letters of reference designate corresponding parts in all the figures.

A designates the shell or chamber of the valve, preferably cylindrical in shape, and B designates a shaft or spindle arranged concentrically within the shell or chamber, and extending upward through a stuffing-box, A', at the top thereof.

C designates the water-inlets, of which two are here represented, and which are arranged transversely, and, as shown, also at right angles to the shell or chamber A. In these water-inlets are formed valve-seats *a*, and *b* designates valves arranged to act in conjunction with said valve-seats and control the flow of water from the supply-pipes into the shell or chamber.

At the back of each valve is preferably arranged a spring, *c*, for aiding in holding it against its seat, and, as here represented, the nipples *D* are constructed to receive said springs, the nipples themselves being secured by nuts or glands *D'*, in the ordinary way.

Where a heavy pressure of water is used the springs *c* may be dispensed with, the pressure of the water being sufficient to insure the proper action of the valves *b*.

At the inner ends of the valves *b* are projections *d*, and the shaft or spindle B is furnished with cams *e*, which, when said shaft or spindle is turned, act upon the projections *d* and upon the valves *b*. As the projections *d* and the cams *e* have approximately flat faces the valves will be held open until the shaft or spindle is turned by hand.

By turning or oscillating the shaft or spindle so as to open either one or both of the valves *b*, either hot or cold water, or both hot and cold water, may be allowed to flow through the delivery outlet or nozzle E and a pipe connected thereto into the basin or other article.

In order to dispense with the ordinary basin-plug, which is liable to become detached and lost, I construct my improved device so that it regulates the flow of the waste water from the basin to which it is applied, as well as the flow of the fresh hot and cold water to the basin.

As here represented, I provide the shaft or spindle B with a piston-valve, F, fitted to a cylindrical portion, A², of the shell or chamber that is bored out to receive it, and adapted to shut down upon a valve-seat, *f*, in the shell or chamber A.

G designates an outlet for the waste water from the basin, opening into the cylindrical portion A², and H designates an outlet for the said waste water from the shell or chamber, in the present instance leading downward from the lower end thereof. Not only can the shaft or spindle B be freely turned or oscillated to control the inflow of water to the basin, but it may be raised to bring the lower end of the valve F above the waste-water inlet G to uncover the latter, thereby affording a free communication between the basin and the waste-outlet H, leading to the sewer.

This form of waste-valve is very advantageous, as it forms a perfect gas-check to prevent the escape of gas from a sewer upward into the basin or other article.

The device here represented is intended to be concealed from view beneath a basin-slab, and a rod is intended to be fitted to the shaft

or spindle B, so that it may be operated by means of a handle located near the basin.

By my invention I furnish a simple device which is adapted to perform all the functions of the separate devices isolated from each other which have hitherto been employed, and it enables wash-basins to be fitted up and connected at less expense.

The overflow-pipe from the basin may be 10 carried downward and connected to the pipe leading from the nozzle or outlet H below the valve; but in this case the flow of gas upward will not be checked by the valve F.

It will be observed that the water which 15 flows out from the basin and enters the faucet or valve when the valve F is raised so as to uncover the opening G cannot flow above the valve F into the portion of the shell or chamber into which the clean water enters, and 20 that the clean water cannot flow into the basin through the waste-water inlet G. This prevents the clean water from becoming contaminated by contact with the waste water.

What I claim as my invention, and desire 25 to secure by Letters Patent, is—

1. The combination of a shell or chamber, a shaft or spindle arranged longitudinally

therein and adapted to be turned or oscillated, two water-inlets extending transversely to said shell or chamber, and each provided with 30 an outwardly-opening valve, and two cams on said shaft or spindle for opening said valves, so arranged that said valves may be opened simultaneously or separately to permit hot and cold water to be drawn separately or together, 35 substantially as specified.

2. The combination of the shell or chamber A, having two inlets, C, and an outlet, E, for fresh water, and outwardly-opening valves b in said inlets, and also having an inlet, G, and 40 an outlet, H, for waste water, the shaft or spindle B, adapted to be oscillated, and provided with two cams, e, so arranged that the inlet-valves may be opened separately or together, and the waste-valve F, attached to said shaft 45 or spindle and adapted to be raised by said shaft or spindle, to afford communication between the waste-water inlet G and outlet H, substantially as specified.

THOMAS HANSON.
